(57) **CLAIM**

The ornamental design for a wall mounted arm and pull up exerciser, as shown and described.

DESCRIPTION

FIG. 1 is a front, right, and top perspective view of a Wall mounted arm and pull up exerciser, wherein at least one weight is on a lower part of a rod, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising a retainer and a pull ring.

FIG. 10 is a partial enlarged view of an area labeled 10 in FIG. 1 comprising gears, a handle, and a portion of a cable; and,

FIG. 11 is another front, right, and top perspective view of the wall mounted arm and pull up exerciser of FIG. 1, wherein the weight body is in an elevated state.

The broken lines shown in the drawings are included for the purpose of illustrating portions of the wall mounted arm and pull up exerciser that form no part of the claimed design.
